LIONEL I. RIVARD, OF NEW HAVEN, CONNECTICUT, ASSIGNOR OF ONE-HALF TO
LAWRENCE F. DWYER, OF TORRINGTON, CONNECTICUT

TOY

Application filed December 22, 1930. Serial No. 504,035.

This invention relates to new and useful improvements in toys and has for its object, among other things, to provide a toy of the moving type that will be fascinating in both 5 its appearance and action, and may be produced at the minimum cost.

To these, and other ends, my invention consists in the toy, having certain details of construction and combinations of parts, as 10 will be hereinafter described and more particularly pointed out in the claims.

Referring to the drawings, in which like numerals of reference indicate like parts in the several figures;

15 Figure 1 is a fragmentary view of my improved toy in side elevation;

Figure 2 is a fragmentary sectional plan view thereof; and

20 Figure 3 is a transverse sectional view thereof, taken generally upon line 3—3 of Figure 1.

In the embodiment of the preferred form 25 of my invention as disclosed herein, I provide a box which is substantially rectangular in shape, having side walls 11, end walls 12 and 13, and open at the top and bottom.

The top of the box member may be closed by a closure member 14, which is secured thereto in any preferred manner, the means 30 herein shown being clips 15 integral with the box walls, which project through openings in the closure member and are bent over onto the top thereof. This box member is carried by two carrier members 17, shown 35 herein as representing Chinese coolies, connected by the cross bars 16.

The legs 18 of these figures are movably connected with the relatively fixed upper portion of the coolies, such as the jacket, and 40 upon the inside thereof by the pins 19, which travel in slots 20. The association of movable legs, with a coolie or the like, and their relative movement by the sequence friction of the legs upon a surface is old in the art 45 and therefore not shown or described herein in greater detail. The cross bars 16 project through openings 21 in the end walls 12 of the box and are held from disengagement therefrom by the closure member 14, the inwardly turned edges 22 thereof resting upon

the top of the cross bar 16, as shown in Figure 1. The feet of the coolie figures rest upon the surface upon which the toy is placed and thus give the appearance of two human figures carrying a weight therebetween.

55 Within the box member is a spring motor which may be of any conventional form. As shown, it comprises a spindle 23, having a key 24 on the outer end and wound there-around is a spring 25, one end of which is fixed to the pinion 26, the teeth of which mesh with those of a gear 27 upon a crank shaft 28. This latter gear meshes with pinion 29 fixed on a shaft 30, upon which, near the opposite ends thereof, and inside of the 60 walls 11, are the wheels 35, the periphery of which rests upon the surface upon which the toy is placed. A portion of the end wall 12 is turned inwardly to form the cheeks 31 between which is pivoted a member 32, shaped 65 like the head and shoulders of a dog. Between this latter member and the crank on the shaft 28 is a connecting rod 33.

70 As the shaft 28 rotates through the action of the spring motor, the member 32 is caused to rock upon the pivot mounting 34 through the connecting rod 33, thus simulating the movement of a dog projecting its head into and out of a kennel. This dog's head is in such close proximity to the carrier at the 75 right of the figure as to give the appearance of attempting to grasp and bite the legs thereof.

80 In operation the motor is wound up through the key 24 and the spring motor causes the same to move on the surface upon which it is placed by reason of the traction of the wheels 30. As the toy is supported by an unyielding support, the wheels 35 in the center, and at its outer ends by the movable supports, the legs 18 of the coolies, in practice, it rocks slightly when in motion upon the wheels 35 due to the shifting of the weight from one foot to the other as the feet of the carrier members successively engage the surface upon which the toy is moving. This results in the weight being thrown onto one of the feet of each of the coolies, which remains stationary in respect thereto 85 and the other foot moves forward. The lat- 90

95

100

ter foot then takes the weight and the rear foot is moved forward through the pivotal connection between the legs and the body of the coolie. Thus, the toy has the appearance of being carried by two moving figures, the legs of which move backward and forward very much like those of a human figure. During these operations the head of the dog 32 is moved into and out of the box member and toward and away from the legs of the carrier at the right of the figure.

5 A tie bar 36 may be provided, if desired to reinforce the wall 12 adjacent to the cheeks 31.

10 This toy is quite attractive in its appearance and the near resemblance to human figures of the coolies forming part thereof makes the toy extremely fascinating and interesting.

15 The box member may be utilized also for display purposes.

20 What I claim as new is:—

25 1. A toy having a box member; a carrier member upon each of two sides of the box member; a bar connecting the carrier members and passing through the box member; traction wheels supporting the box member; a spring motor within the box member to rotate the wheels; and an in-and-out member 30 in the form of the head of an animal or the like movably connected with the box member and actuated from said motor.

35 2. A toy having a box member; a carrier member upon each of two sides of the box member; a bar connecting the carrier members and passing through the box member; traction wheels supporting the box member; a spring motor within the box member to rotate the wheels; a crank shaft actuated by 40 the spring motor; an in-and-out member, in the form of the head of an animal or the like, movably connected with the box member; and a member between the crank shaft and the in-and-out member, whereby a rocking motion is given to said member from the 45 crank shaft.

50 3. A toy having a box member with an opening through one wall thereof; an in-and-out member in the form of the head of an animal or the like pivotally connected to the box member and movable therethrough; a carrier member upon each of two sides of the box member so positioned that one of said carrier members is in front of said opening; 55 a bar connecting the carrier members and passing through the box member; traction wheels supporting the box member; a spring motor within the box member providing a source of power to rotate said wheels; a crank 60 shaft journaled within the box member and actuated by said motor; and a connecting member between the crank shaft and said in-and-out member, whereby during the rotation of the crank shaft a rocking motion 65 is imparted to the in-and-out member, which

is thereby caused to move in a substantially in-and-out path toward and away from the adjacent carrier member.

In testimony whereof I have hereunto affixed my signature.

LIONEL I. RIVARD.
